UNITED STATES PATENT OFFICE

WALTER E. SKIDMORE, OF EAST LIVERPOOL, OHIO

MOLDING MACHINE

Application filed October 13, 1928. Serial No. 312,323.

This invention relates to improvements in molding machines and constitutes an improvement upon my former Patent No. 1,262,276.

5 The present mold is designed particularly for use in the forming of insulators and has for its particular object to provide a machine of greater efficiency than my former machine, and in which an improved means is 10 employed for operating the side mold toggle arms by means of which the same can be swung through greater arcs for the performance of their various operating movements.

Another object of the present invention is 15 to provide a machine of the above described character designed to be operated by mechanical power, making use of a new and novel means for vertically reciprocating the plunger of the machine.

20 A still further object of the invention is to provide a molding machine of the above described character wherein is employed a novel type of molded article extracting mechanism designed to operate immediately following the separation of side dies to strip the article from the center or core die.

The invention will be best understood from a consideration of the following detailed description taken in connection with the accompanying drawings forming part of this specification, with the understanding, however, that the invention is not confined to any strict conformity with the showing of the drawings but may be changed or modified 30 so long as such changes or modifications mark no material departure from the salient features of the invention as expressed in the appended claims.

In the drawings:—

40 Figure 1 is a front elevation of the device embodying the present invention;

Figure 2 is a side elevation of the same, partly broken away;

45 Figure 3 is a vertical sectional view showing the mold elements and the mechanism for removing the molded article;

Figure 4 is a horizontal sectional view on the line 4—4 of Figure 1;

50 Figure 5 is a horizontal sectional view on the line 5—5 of Figure 1;

Figure 6 is a vertical sectional view on the line 6—6 of Figure 5;

Figure 7 is a sectional view taken on the line 7—7 of Figure 4.

Referring more particularly to the drawings, the numerals 1 indicate a pair of upright side beams of the frame of the present mold, these beams being mounted in a suitable manner upon the base 2 and connected at their upper ends by a plunger guide beam 3 and at a point intermediate their ends and adjacent the beam 3, by a second or brace beam 4. The central portion of the beam 3 has a recess formed therethrough as indicated at 5, this recess being normally covered by a plate 6 which acts to maintain a plunger, hereinafter described in upright position.

Adjacent their lower ends, the side members 1 of the frame are connected by a charge receiving receptacle supporting beam or platform 7 in the central portion of which is mounted the charge receiving receptacle 8.

At the rear of each of the frame members 1, there is located an upright beam 9, these beams being mounted upon the base 2 and connected at their upper ends to the members 1 by the horizontal pieces 10. The members 9 are also connected together by an upper beam 11 and an intermediate beam 12, the beam 12 being designed to support a drive shaft 13, upon the outer end of which a suitable pulley 14 is mounted.

At its forward end the shaft 13 is rotatably mounted in a suitable bearing formed in an upright plate 15, which plate is located midway between the side members 1, resting at its lower end upon the base 2 and its upper end being connected to the receptacle supporting beam 7 in the manner shown.

A pinion 16 is mounted upon the forward end of the shaft 13, which meshes with a gear 17 suitably rotatably mounted upon the plate 15, this gear being provided with an eccentric pin 18 which connects with a horizontal lower drive beam 19. As shown this drive beam 19 extends transversely of the machine frame, having its ends extended through vertical slots 20 formed in the lower portions of the members 1.

The outer ends of the lower drive beam are

connected by adjustable drive links 21 with similarly projecting ends of a substantially horizontal upper drive beam 22, this upper drive beam extending transversely of the 5 machine frame and having its ends extending through long guide slots 23 formed longitudinally through the side members and extending through a substantial length of their upper ends. The outer ends of the beam 22 10 are provided with a series of apertures 24 so that adjustment of the upper ends of the links 21 may be made longitudinally thereof. Connected intermediate its ends to the upper drive beam 22 at the center thereof is 15 a vertically arranged reciprocable plunger 25 which extends downwardly through the recess 5 in which it is held by the plate 6. As shown this plunger, adjacent its lower end, has formed therethrough a longitudinally ex- 20 tending slot 26', the lower portion of which slot opens into a longitudinally extending bore 27, the lower portion of which bore is enlarged as indicated at 28 and opens through the lower end of the plunger. As is shown 25 in Figure 3 the lower end of this bore is threaded.

The bore 27 has positioned therein an ejector pin member 29 which extends downwardly therethrough projecting beyond the lower 30 portion of the plunger and extending into a longitudinally extending bore 30 formed in a central die member 31. This core die member 31 as shown has threaded connection in the lower end of the enlarged portion 28 of 35 the bore and the wall of the die is provided with the diametrically oppositely positioned longitudinally extending slots 32 in which reciprocates the ends of a transverse pin 33 which is carried by the lower end of the 40 ejector pin 29. The pin 29 also carries a disk 34 which snugly slidably positions in the enlarged portion 28 of the bore 27 limiting the upward movement of the pin and acting as an abutment for the upper end of 45 a coiled spring 35 encircling the pin therebeneath and resting upon the upper end of the center or core die 31 in the manner shown.

Surrounding the die 31 is an ejector sleeve 50 36 with the upper end of which the ends of the pin 33 connect so that movement of the pin 33 will cause the sleeve 36 to slide upon the center die 31.

Positioned in the recess 26 of the plunger 55 is a roller member 37 having a shaft 38 extending therethrough and each end of this shaft has sliding pivotal connection in an ar- 60 cuate slot 38' formed through each of a pair of crossed toggle links 39, the connection being made adjacent the lower ends of the links as shown in Figure 1. The upper ends of these links connect with roller members 40 while the lower ends thereof pivotally connect as at 41 with the lower ends of die 65 carrying links 42, these links 42 being located

upon opposite sides of the plunger 25 and each extending upwardly between a pair of toggle links 39 and adjustably pivotally secured at its upper end to the upper drive beam 22 as indicated at 43.

At its lower end, each of the die links 42 70 carries a semi-circular side die member 44 which co-operates with the central die 31 to form the product for which the machine is constructed.

Adjustably secured to the inner face of each side member 1 adjacent the brace beam 4 is a block 45 over the inner face of which the rollers 40 of the adjacent pair of toggle links 39 passes during the operation of the machine. These blocks are secured in adjusted position by bolts 46 which pass therethrough and through the slots 23 in the supporting frame member being held to the frame member by tightening a nut upon the outer end of the bolt to bind the block against the frame in the manner shown. Arranged against the inner face of each side member 1 adjacent and to overlie the stationary die supporting beam 7 is a lower block 47, each of these blocks carrying bolts 48 which pass therethrough and through the lower ends of slots 23, the block being bound to the frame in the same manner in which the blocks 45 are secured thereto, that is by the application of a suitable nut upon the outer end of the bolt to draw the bolt and block into position.

The block members 47 coact with rollers 49 mounted upon and projecting laterally from the lower ends of the die links 42 to maintain the die halves 44 tightly together about the core 31 when a molded body is being formed.

In operating the present machine, the receptacle 8 which is formed to snugly receive the center die 31 and side dies 44 when they have been brought to position thereabout, is charged with a suitable amount of plastic material to be molded such as clay or the like and upon application of suitable driving power to the gear 17 the drive beams 19 and 22 will be drawn downwardly, thus bringing the plunger 25 down and causing the center and outside dies to enter the material contained in the receptacle 8. During the first part of this downward movement the rollers 40 of the toggle links will move inwardly and down the faces of their respective blocks 45, thus operating the toggle links 39 to swing the side dies 44 together, causing them to encase the central die 31.

As the dies move into position in the receptacle 8, the plastic material therein is forced upwardly into the space between the side dies and the central die. The side dies 44 are caused to press firmly together by the passing of the rollers 49 which are carried upon the lower ends of the die links 42 over the inner faces of the lower blocks 47. During the downward movement of the plunger and while the same is at its lowermost point, the 120 125 130

roller 37 which occupies the slot 46 in the plunger assumes a position in the slot above the pin 29.

After the insulator body has been formed, or in other words, after the pin 18 has swung beyond its lowermost position on the drive gear 17, the reverse or upward movement of the beams 19 and 22 is begun.

This upward movement first causes a release of the pressure of the side dies 44 against the material interposed between them and the center die 31 by the movement of the rollers 49 off of the inner faces of the blocks 47. Further upward movement of the beams and of the links 42 brings the rollers 40 of the toggle links to position where they can move laterally over the tops of the blocks 45, their further upward and lateral movement being stopped by the brace beam 4 and the side members 1 against which they abut. This operation causes the lower ends of the toggle links to swing apart in the manner shown. As is clearly shown in Figure 1 when the links have reached the positions above described, that is the position where the side dies are entirely free of the insulator carried upon the core die 3, the pivotal connection 18 between the gear 17 and the beam 19 will not have reached the limit of its movement upward. The continued rotation of the gear 17 forces the plunger 25 upwardly thus bringing the upper end of the ejector pin 29 against the roller 37 forcing it, and the sleeve 36, downwardly, the sleeve sliding on the core die to push off the formed insulator.

It is of course, clear that owing to the fact that the links 39 cannot move further laterally at their upper ends, in order to permit their lower ends to shift in order to allow the attached links 42 to move with the plunger 25, the arcuate slots 38' are provided. It will be readily seen that as an upward pull is exerted upon the links 42 their lower ends will be swung further apart because of the pivotal connection at 41 with the links 39 and the slots 38' are provided to permit the links 39 to have sufficient swinging movement to permit this action.

In order to maintain the plunger 25 in the proper position an adjusting means is provided which comprises four screws each of which is indicated by the numeral 50. These screws are threaded through supporting blocks 51 located adjacent each corner of the plunger 25 as shown in Figure 4 and each carries upon its forward end the swivel head 52 formed to receive the adjacent corner of the plunger. As will be readily seen upon referring to Figure 4 the four screws 50 may be adjusted so that the plunger 25 will be held in the proper position for vertical reciprocation.

In order to make the operating action of the upper ends of the links 39 more positive there is provided a spring 53 for attachment

at one end to the upper ends of these links, each of the springs being extended through the adjacent recess or slot 23 to the outside of the frame where it is attached to the adjacent bolt 46. It will be seen that when the links 39 are drawn together the springs 53 will be placed under tension and will operate to make the return of the links positive.

From the foregoing description, it will be readily understood that the machine herein described constitutes a simple and efficient means for rapidly forming insulators and other pressed articles of this character, the machine being of strong and rugged construction and comparatively inexpensive to set up and operate.

Having thus described my invention, what I claim is:

1. A molding machine of the character described, comprising a receptacle, a vertically reciprocable plunger, a center mold carried by said plunger, side molds arranged upon opposite sides of the center mold, said center mold and side molds being designed to enter the receptacle, crossed toggle arms pivotally connected intermediate their ends each controlling at its lower end one of said side molds and having its other end free, roller members carried upon the free ends of the toggle arms, and guide elements adjustably mounted at opposite sides of the plunger for governing the movements of the roller carrying ends of the toggle arms.

2. A molding machine of the character described, comprising a receptacle, a vertically reciprocable plunger, a center mold carried by said plunger, side molds arranged upon opposite sides of the center mold, said center mold and side molds being designed to enter the receptacle, crossed toggle arms pivotally connected intermediate their ends each controlling at its lower end one of said side molds and having its other end free, roller members carried upon the free ends of the toggle arms, guide elements adjustably mounted at opposite sides of the plunger for governing the movements of the roller carrying ends of the toggle arms, and means controlled by the toggle arms at a certain period in the operation of the machine for ejecting a molded article from said center mold.

3. A mold machine of the character described, comprising a frame including a pair of spaced upright side members, a receptacle arranged between said side members, a transversely extending vertically reciprocable operating beam carried by the side members, a vertically mounted plunger carried by said beam in alinement with said receptacle, a center mold carried by said beam, means for supporting a pair of side molds at opposite sides of said center mold, crossed pivotally connected toggle arms each connected at its

lower ends with a side mold, and means for controlling relative movement of said toggle arms during the operation of the machine for separating or bringing together said side molds about the center mold.

5. A mold machine of the character described, comprising a frame including a pair of spaced upright side members, a material receptacle arranged between said side members, a transversely extending vertically reciprocable operating beam carried by the side members, a vertically mounted plunger carried by said beam in alinement with said receptacle, a center mold carried by said beam, means for supporting a pair of side molds at opposite sides of said center mold, crossed pivotally connected toggle arms each connected at its lower ends with the side mold, means for controlling relative movement of said toggle arms during the operation of the machine for separating or bringing together said side molds about the center mold, and means for adjusting said last mentioned means for increasing or decreasing the time period of operation of the toggle arms.

6. A mold machine of the character described, comprising a frame including a pair of spaced upright side members, a material receptacle arranged between said side members, a transversely extending vertically reciprocable operating beam carried by the side members, a vertically mounted plunger carried by said beam in alinement with said receptacle, a center mold carried by said beam, means for supporting a pair of side molds at opposite sides of said center mold, crossed pivotally connected toggle arms each connected at its lower ends with the side mold, means for controlling relative movement of said toggle arms during the operation of the machine for separating or bringing together said side molds about the center mold, means associated with said plunger for removing a formed article from the center mold after the same has been extracted from the stationary mold, and means carried by the toggle arms for operating the article removing means.

7. A mold of the character described, comprising a receptacle, a vertically reciprocable plunger arranged over said receptacle, a central die carried at the lower end of said plunger, means for reciprocating said plunger, depending link members carried by said means at opposite sides of the plunger, a pair of side dies each carried by one of said links, said dies being designed to close about the central die, crossed toggle arms pivotally connected intermediate their ends and having the pivotal connection extending through a longitudinal slot in the plunger, said toggles each being pivotally connected at its lower end to one of said links, means acting upon the other ends of the toggle arms for causing relative movement therebetween during the operation of the plunger, and means actuated

by the toggle arms for causing the stripping of a formed article from said central die when the side dies are in open position.

7. A molding machine having a vertically reciprocable plunger carrying a center die at its lower end and having a pair of laterally shiftable side dies arranged on opposite sides of the central die and means for stripping a formed article from the center die after the same has been formed thereabout between the side dies and in a receptacle, comprising a sleeve surrounding the central die inwardly of the position occupied thereon by a molded article, a reciprocating pin operating within a central passage formed in the plunger and extending into the central die, lateral pins carried by the first-mentioned pin extending through longitudinal slots in the central die for engagement with said sleeve, the upper end of the first-mentioned pin projecting into a slot formed longitudinally through the plunger, resilient means normally retaining the first-mentioned pin in retracted position, a pair of toggle arms crossed intermediate their ends and each having connection with one of said side dies, a pivot pin extending through the toggle arms and through said plunger slot for engagement with the first-mentioned pin, and means for causing relative movement between the toggle arms during the operation of the machine for operating the ejector mechanism.

8. A mold of the character described, comprising a frame including a pair of upright side members each having longitudinally extending slots therethrough adjacent the upper and lower ends thereof, transversely extending upper and lower power beams having their ends extending through adjacent ones of said slots, adjustable connecting links between the adjacent ends of the beams, a plunger carried by the upper beam, depending link members carried by the upper beam at opposite sides of the plunger, a die unit co-operating with a material receptacle and including a central die member carried by said plunger and side die members arranged on opposite sides of the central member and carried by said links, toggle arms crossed intermediate their ends and having pivotal sliding connection with said plunger, the lower ends of said toggle arms being pivotally connected to adjacent links, means acting upon the other ends of the toggle arms during the operation of the machine for causing relative movement therebetween, and driving means connected to the lower ones of said power beams for raising and lowering the same.

9. A molding machine of the character described comprising a receptacle, a plunger, a center mold carried by said plunger, side molds arranged upon opposite sides of the center mold, said center mold and side molds being designed to enter the receptacle, crossed toggle arms pivotally connected intermediate

their ends each controlling at its lower end one of said side molds and having its other end free, and guide elements mounted at opposite sides of the plunger for governing the 5 movements of the free ends of the toggle arms.

10. A molding machine of the character described comprising a receptacle, a plunger, a center mold carried by said plunger, side 10 molds arranged upon opposite sides of the center mold, said center mold and side molds being designed to enter the receptacle, crossed toggle arms pivotally connected intermediate their ends each controlling at its lower 15 end one of said side molds and having its other end free, guide elements mounted at opposite sides of the plunger for governing the movements of the free ends of the toggle arms, and means operated by said arms at 20 a predetermined period of their movement for stripping a molded article from the center mold.

In testimony whereof I hereunto affix my signature.
